UNITED STATES PATENT OFFICE.

LIPA POLINKOWSKY, OF BRUSSELS, BELGIUM, ASSIGNEE, BY MESNE ASSIGNMENTS, TO
WESTERN ELECTRIC COMPANY, INCORPORATED, A CORPORATION OF NEW YORK.

MACHINE TELEPHONE SYSTEM.

1,193,053.

Specification of Letters Patent.

Patented Aug. 1, 1916.

Application filed March 5, 1914. Serial No. 822,590.

To all whom it may concern:

Be it known that I, LIPA POLINKOWSKY, a subject of the Emperor of Russia, residing at Brussels, in the Kingdom of Belgium, 5 have invented a certain new and useful Improvement in Machine Telephone Systems, of which the following is a full, clear, concise, and exact description.

This invention relates to machine telephone switching systems and more particularly to a system of metering for use in such systems.

It is an object of the present invention to provide a metering system in which the operation or non-operation of a meter is automatically controlled independently of any operator or attendant at the exchange. In accordance with this object a metering device and circuit arrangements therefor are 20 provided so that a meter individual to a subscriber's line is controlled by means of differentially operating devices to cause the registration of a charge if a desired connection to a called line from a calling line with 25 which such meter is associated has been successful and to prevent the operation of such meter if such connection has been unsuccessful.

For the purpose of clearly disclosing the 30 operation of the metering system of the invention such system is shown and described as applied to a complete machine telephone system, which machine telephone system contains several novel features which do not 35 form a part of this invention and are not claimed herein. The particular devices and circuits, therefore, by which this is accomplished will be more fully disclosed and understood from the following description 40 taken in connection with the accompanying drawings in which—

Figures 1 and 1^a show circuits and apparatus of a subscriber's line and a first line finder adapted to extend the connection of 45 such line when calling. Figs. 2 and 2^a illustrate diagrammatically the second line finder and the connecting circuit associated therewith, together with the group selector. Figs. 50 3 and 3^a illustrate the circuits and apparatus of the final selector. Figs. 4 and 4^a illustrate a circuit and apparatus of the registering and controlling equipment adapted to be 55 associated with the connecting circuit shown in Fig. 2 to control the group selector and final selector shown. Fig. 5 is a detail view

of a portion of the final selector. Figs. 1, 1^a, 2, 2^a, 3, 3^a, 4 and 4^a taken together illustrate diagrammatically a system involving the invention.

The figures should be arranged as follows:—from left to right, Figs. 1, 1^a, 2, 2^a, 3 and 3^a, and Fig. 4 should be placed under Fig. 2 and Fig. 4^a under Fig. 2^a.

The line finders, group selectors and sequence or steering switches are of types already known in the art and need not herein be specifically described, it being sufficient to describe their relation with the circuits. Also the method of showing the sequence switch contacts and the indication of the operating positions of the sequence switch is well understood, and mention need only be made that in Fig. 2 the sequence switch contacts of the three sequence switches shown thereon are associated with the sequence switch indicated in that portion of the figure separated from the remaining portions by dotted lines.

The mechanical construction of the registers of the registering and controlling equipment, it is thought, will be sufficiently understood from the diagrammatic showing thereof and the description of their operation.

The final selector switch differs from the final selector switches of this type previously known only by the addition of two extra notches in the interrupter plate of the top thereof, between the first 10 notches thereof and the second 10 notches thereof. It will be recalled that selector switches of this type have a capacity of two hundred lines, and the contacts of these lines are arranged in ten levels of twenty lines each. Between the bank of the one hundred lines individual to one hundred, and the bank of lines individual to another hundred, that is to say, between the first ten lines of each level and the second ten lines of each level there is a spacing plate. In selector switches of this type previously known the spacing between the two banks of line contacts was without effect, as the interrupter plate at the top of the selector was uncut over the portion thereof corresponding to the spacing plate. In the final selector switches as used herein, however, there are two notches cut in the portion of the interrupter plate corresponding to the spacing plate for purposes herein described. That is to say, in selecting a line

in the first set of ten lines on a given level, the interrupter will operate a number of times corresponding to the number of lines passed over, whereas, in selecting a line in 5 the second set of ten contacts on such given level, the interrupter will operate a number of times corresponding to the number of lines passed over plus two. This will be readily understood from an examination of 10 Fig. 5 in which the notches *a* represent the notches of such interrupter plate corresponding to the first set of ten lines on the given level of the selector; the notches *b* represent the notches in such plate corresponding to 15 the second set of ten lines on such level, and the two notches *c* represent the two extra or additional notches which have been added as above indicated for purposes hereinafter described.

20 The invention as disclosed herein will be best understood from a description of the operation of the system shown.

Assuming that the subscriber at the substation indicated at 120 desires connection 25 with the subscriber indicated at 320, whose number is 307, he first removes his receiver from its switchhook, thereby closing a circuit for the line relay 121, which on its energization closes a circuit for and energizes 30 the pilot relay 122 common to a group of incoming lines which appear multiplied upon a given group of first line finders such as the one shown in Fig. 1. Relay 122 closes a circuit over the sequence switch springs 104 and 103 for the power magnet 123 of all the 35 first line finders of this group which are at this time in idle condition; that is, whose sequence switches 100 are in first or normal position. Such idle line finders will, therefore, start in motion, moving their brushes 125, 126, 127, 128 over the terminals 129, 130, 131, 132 of the lines appearing in such line finders, and testing such lines in the usual way. As one of them, however, brings 45 its brushes into contact with the terminals of the calling line, it will find upon the terminal 132 of such line a selectable potential produced by the energization of the line relay 121 and determined by the resistances 50 133 and 134. Immediately that the brush 128 comes in contact with the terminal 132 upon which such selectable potential exists, the test relay 135 will be energized over the springs 102 bottom, 108 top and either the 55 spring 106 or the interrupter brush 136. The energization of this relay 135 closes through its armature a circuit through its low resistance holding winding for itself the closure of such circuit through such 60 winding so reducing the potential upon the terminal 132 that such line is no longer selectable, and any other line finder whose brush 128 comes in contact with such terminal 132 will not be stopped. The carriage 65 of the line finder which has thus seized the

line, continues in motion, however, until its brushes are properly centered upon the terminals of the calling line, at which time the circuit through the interrupter brush 136 will be open, and the shunt being removed 70 from around the power control test relay 137, such relay will be energized, opening the circuit of the power magnet 123 and closing the circuit of the holding magnet 138 over the springs 105 top and 107, thereby 75 positively stopping the brush carriage in proper position. The energization of the relay 137 has also driven the sequence switch 100 out of its first into its second position. In this movement of the sequence switch a 80 test guard is maintained upon the terminal 132 and the seized line through the spring 112 bottom, the spring 102 bottom being opened as the sequence switch leaves its first position. In the second position the spring 85 110 being closed, the cut-off relay 139 of the calling line is energized, causing the de-energization of the line relay 121 and the consequent de-energization of the pilot relay 122, provided no other line of this group is 90 at this time calling and not as yet been seized by a line finder. The meter 55 individual to the line is connected as shown in parallel with the cut-off relay 139 also individual to such line. However sufficient current will 95 flow over the circuit just traced to cause the energization of cut-off relay 139, but sufficient current will not flow over this circuit to cause the energization of the meter magnet. The de-energization of the relay 121 100 opens the battery circuit to the terminals 132, and the line now having been seized and being maintained busy, no selectable potential is possible upon its test terminal 132.

The sequence switch 100, on coming into 105 its second position, has established a circuit over spring 113, the pilot wire, and the springs 602 bottom, back contact of relay 237 and spring 603 top for the power magnets 226 of the idle second line finders in 110 which the circuit connected to the first line finder shown appears in multiple. The brush carriages of such idle line finders, therefore, move the brushes 227, 228, 229, 230 over the contacts 231, 232, 233, 234 of 115 the various lines appearing in such line finders. The sequence switch 100, on coming into its second position, by closing the springs 108 bottom, 106 top and 107, has placed selectable potential on the terminal 120 234 of the trunk line or circuit connected to the first line finder associated with such sequence switch 100. When the brush 230 of one of such second line finders comes in contact with the terminal 234, upon which 125 this selectable potential exists, the test relay 235 will be energized, the circuit for such relay including the springs 604 top, 605 top and either the interrupter brush 236 or the spring 606 top. Such relay 235 will, there- 130

fore, be energized, closing in parallel to its right-hand winding a circuit including the low resistance holding winding, which will so reduce the potential upon the terminal 234 that no other second line finder can now 5 seize the line to which such terminal is individual. The brushes of the seizing second line finder, however, will continue to move until when they are centered upon the terminals of the seized line the circuit over the 10 interrupter brush is opened, and, the shunt being thereby removed from around the power-control test relay 237, such relay is energized to stop the switch in the usual manner by opening the circuit of the power magnet 226 and closing the circuit of the holding magnet 238, at the same time driving the sequence switch 600 out of its first 15 into its second position by closing a circuit over the spring 607 top.

As the sequence switch 600 leaves its first position, and until it has passed through its seventh position, a busy test guard is maintained upon the terminal 234 by the closure 20 of the spring 610, connecting ground to such terminal.

As the sequence switch 600 was passing from its first into its second position, the spring 611 was closed sufficiently long to 30 drive the sequence switch 203 out of its first position, the circuit for moving such sequence switch including the spring 202 bottom. This sequence switch comes to rest in its second position.

In position 2 of the sequence switch 600, and in position 2 of the sequence switch 200, the selection of an idle registering and controlling mechanism will take place. Before 35 considering this operation, however, the various effects of the seizure of the circuit connected to the first line finder, and the movement of the sequence switch 200 into position 2 will be considered. When the test relay 235 was energized, the circuit therefor also included the relay 137, to maintain it 45 energized, and relay 137 being energized the sequence switch 100 is moved from its second position to its fifth position.

In position 5 the circuit for relay 137 will 50 include the resistance 140 as well as the resistance 141, but such relay will be maintained energized so long as the spring 610 top is closed.

In position 5 of the sequence switch 100, 55 the spring 110 being open, the circuit for the cut-off relay 139 now includes the spring 102, the relay 135 and the spring 207, the sequence switch 200 now being in the second position. In this position also the spring 60 112 is open and the circuit of the calling line is extended over the springs 210 top and 211 top to the repeating coil 239.

As the sequence switch 600 came into its 60 second position, the springs 604 bottom, 619 top, 605 bottom, 606 bottom and 613 bottom

were closed. If at this time the sequence switch 700 individual to the connecting circuit shown is in such position that an idle registering and controlling equipment is connected by it to the leads shown, the relay 70 75 240 will be energized over a circuit including springs 703, 619 top, 604 bottom, 704 bottom, relay 426 and spring 405 of the sequence switch 400 individual to such idle registering and controlling equipment. If, however, the equipment with which the leads are connected over such sequence switch 700 is already busy, the test circuit including the relay 240 of some other connecting circuit will already be energized over the 80 circuit including the relay 426 and insufficient current will pass through the relay 240 shown, to energize it. A circuit will, therefore, be established over the back contact of such relay 240, spring 613 bottom and 85 spring 702 to cause the sequence switch 700 to move and it will continue in motion until on closing the circuit from the leads of the connecting circuit to the leads of an idle equipment the relay 240 is energized, at 90 which time the circuit over the sequence switch 700 will be opened and the relay 237 being energized in parallel with the relay 240 the sequence switch 600 will be driven through sequence switch springs 602 top 95 and 607 top from its second into its third position. In this position the relay 240 and the relay 237 are directly connected over the spring 619 bottom and over the spring 704 bottom, for example as shown, to the 100 starting relay 426. This idle registering and controlling equipment is now seized and is inaccessible to any other connecting circuit having access thereto until it has performed its function or has been released by the 105 hanging up of the receiver of the calling subscriber, as will be hereinafter described.

As the sequence switch 600 moved into its third position it closed the circuit over the spring 609 to drive the sequence switch 200 110 also to its third position. In this position springs 210 bottom and 211 bottom are closed, and the impulse receiving circuit from the subscriber's substation to the registering and controlling equipment is now 115 complete, such circuit being traceable from battery through the stepping relay 427, spring 402 of the sequence switch 400, spring 707 bottom of the sequence switch 700, spring 210 bottom of the sequence switch 200, brush 122 and terminal 232 of the second line finder switch, brush 126 and terminal 130 of the first line finder switch over the subscriber's line and through his substation, terminal 129 and brush 125 of the first line finder switch, 125 terminal 231 and brush 227 of the second line finder switch, spring 211 bottom to ground and back to battery.

The relay 426 being energized, as before described the sequence switch 400 is driven 130

out of its first and into its fourth position. It will be observed that the calling subscriber's supervisory relay 241, which at this time controls restoration and which in 5 position 2 and position 4 and positions subsequent thereto is directly under the control of the calling subscriber, is energized by the closure of a spring 205. The apparatus will now await the sending of impulses 10 by the calling subscriber, such impulses being arranged in groups corresponding to the complement of the digits of the numerical designation of the called subscriber's station—that is to say, the called subscriber's 15 number being assumed to be 307, the calling subscriber will transmit to the central station three series of impulses, the first series comprising seven impulses, the second series comprising ten impulses, and the third series 20 comprising three impulses. In each of these series of impulses the last impulse sent will be relatively longer than the other impulses of the series, which other impulses are in fact quite short. The sender by which 25 these impulses are sent may be of any desired structural character, provided that the impulses are sent in a complementary manner, and that the last of each of the groups of impulses sent by such device is relatively 30 longer than the other impulses of such group. A sender is diagrammatically shown capable of accomplishing the necessary functions, and in which the setting of the sender produces no impulse in the circuit. The impulses 35 as produced in the system as disclosed are interruptions of the circuit.

The system herein disclosed is for clearness shown only as a 1000 line system. In such a system there will be five groups of 40 final selectors, each accessible to 200 lines thereof, and the group selectors used will have only five of the ten banks thereof utilized, one bank of contacts being connected to the trunk lines of the group of final 45 selectors individual to one group of 200 lines, another connected to another group of final selectors individual to another 200 lines, and so on. In accordance with the translating system disclosed herein, the selection in the 50 group selector of the trunk line leading to the group of lines having the proper hundreds digit is such that if the 100's digit of the desired line is zero or one, the tripping spindle of the group selector will be adjusted to release the proper set of brushes on 55 the brush carriage by the movement of such spindle one step or stage. If the 100's digit of the desired line is two or three, such spindle will be moved three steps or stages. If 60 the 100's digit is four or five, the spindle will be moved five steps or stages. If the 100's digit is six or seven, such spindle will be moved seven steps or stages, and finally if the 100's digit is eight or nine, such spindle 65 will be moved nine steps or stages. Of

course, it will be understood that if the system is for more than 1000 lines, the intermediate steps or stages, that is, second, fourth, sixth, eighth and tenth will be reserved for use when a trunk line is desired leading to 70 the groups of selectors having access to the lines of such second thousand. In a 1000 line system as herein disclosed, the trunk lines may be, and it will be assumed are, connected to the alternate levels of contacts in 75 such group selector. It will be further understood that by properly rearranging the tripping teeth upon the tripping spindle, the five levels and terminals which are used may be arranged, if desired, adjacently to 80 each other, so that the first level will be selected by a single step of the tripping spindle, the second level by three steps of such spindle, the third level by five steps of such spindle, and so on. Furthermore, if 85 preferred the arrangement of the lines of the subscribers upon the final selectors may be so arranged that the trunk line leading to a corresponding group of 100 in each of the two thousand lines accessible through a group 90 selector will be selected in the same level of such group selector, such arrangement resulting in the selection of a line whose 100's digit is zero in either thousand by one step of the tripping spindle of the group selector, 95 a line whose 100's digit is 1 by two steps of the tripping spindle, and so on. As shown, however, the arrangement of the lines and the selection in the group selector will take place as first above described.

An operation, therefore, of the subscriber's sending mechanism to send the 100's digit 3 will produce seven breaks in the circuit hereinbefore described, including the stepping relay 427, the last of such breaks 105 being relatively longer than the others of the group. Upon the initial energization of the stepping relay 427 a circuit was closed by its armature over the spring 408 and the back contact of the changeover relay 428, 110 including the lower winding of the 100's register 429. This causes the energization of the power magnet of such register and it moves until when midway between its zero or normal position and its first position, its 115 local positioning or A spring 471 is closed. At this time a circuit is closed over the front contact of the relay 426 and such positioning spring through the upper winding of this register. The two windings of the 120 register are differentially wound on the power magnet thereof, so that when a circuit is closed through both of said windings, or when there is a circuit through neither of said windings, such register will stop; 125 whereas, when a circuit is closed through but one of said windings the register will move. The register 429, having therefore been brought to rest between its zero and first positions, will await the opening of the 130

circuit through its lower winding at the front contact of the stepping relay 427 before moving farther. Therefore, as the result of the first interruption in the circuit in the operation of the subscriber's sending mechanism, and the consequent deenergization of the stepping relay 427, the register will move into its first position, the circuit of the upper winding thereof being closed 10 through the positioning spring 471. Upon the cessation of the first interruption, the relay 427 is again energized, and the register 429 is driven to a position intermediate of its first and second positions, correspondingly in response to the second interruption it will be driven into its second position. Therefore, as the circuit is interrupted seven times, upon the cessation of the seventh interruption the register 429 will be driven 20 into its seventh position. As this interruption is a longer one the stepping relay 427 will be deenergized sufficiently long for its armature to close at its back contact and spring 413 a circuit for the slow operating 25 changeover relay 428 and energize the same. This changeover relay opens the circuit of the register 429 at its right-hand armature in order to prevent any false operation of such register, and closes at its left-hand armature a circuit over spring 404, for the sequence switch 400, driving such sequence switch into its sixth position. The 100's register has now been set, and it may proceed to control selection in the group selector. For this purpose the outgoing sequence switch 450 shown to the right of Fig. 4^a, and whose springs are all to the right of the dotted line, has been started by the closure of the spring 407 bottom as the incoming 30 sequence switch 400 passes through its fifth position. Before, however, describing the selection controlling operation initiated by the movement of the outgoing sequence switch 450, further registering operations 35 will be described.

Upon the reestablishment of the transmitting circuit, and the consequent energization of the stepping relay 427, the circuit through the lower winding of the 10's 40 register 430 will be energized in the sixth position of the sequence switch 400 over the spring 409 top. The group of interruptions now being sent in, comprising ten interruptions (the zero digit being sent), the tens 45 register will be moved to, and come to a stop in its tenth position precisely in a similar manner as that in which the 100's register was set. The last interruption of this group being a relatively longer one, the changeover relay 428 was energized and the sequence switch 400 driven into its eighth position, the 10's register 430 thereby being removed from association with the stepping relay, and the units register 431 being placed 50 under the control of such relay by the clo-

sure of the spring 409 bottom. The closure of the controlling circuit including the stepping relay 427 and its interruption three times to send the digit 7 will cause the units register 431 to move into its third position 70 in the manner now well understood, and the final interruption being a long one, the sequence switch 400 will be driven out of its eighth position by the energization of the changeover relay 428. In its ninth position 75 the incoming switch 400 will remain until at the conclusion of the selection controlling operation it is started in motion to its normal position by a circuit closed by the outgoing sequence switch 450 in returning to 80 normal over the spring 407 top.

The registers have now been set to properly control the selection controlling operations in accordance with the numerical designation of the desired subscriber's line; the 85 100's register has been moved into its seventh position, the 10's register has been moved to its tenth position and the units register moved into its third position. As the incoming sequence switch 400 reached its ninth 90 position a circuit was closed over the spring 412, and the spring 206 bottom, to drive the sequence switch 200 out of its third into its fourth position, in which position the supervisory relay 241 is again placed under 95 the control of the calling subscriber, and the sending circuit from the calling substation is open at the springs 210 bottom and 211 bottom.

The outgoing sequence switch 450 of the 100 registering and controlling equipment, when it was moved from its first position as the incoming sequence switch 400 passed through its fifth position, as above described, continued in motion until it reached its fourth 105 position. In passing from its first to its second position, a test was made by the spring 459 to determine whether the 100's digit of the number registered was odd or even; it having been found to be odd, the 110 hundreds register is in its seventh position, seven impulses having been sent by the calling subscriber operating his sending mechanism for the digit 3, a circuit was closed for the translating relay 432. It will be observed that the spring 474 of the 100's register is closed in the following positions; 115 only a few of which, for clearness, are indicated upon the drawings:—

$\frac{1}{2}$	to	1	120
2 $\frac{1}{2}$	"	3	
4 $\frac{1}{2}$	"	5	
6 $\frac{1}{2}$	"	7	
8 $\frac{1}{2}$	"	9	
10 $\frac{1}{2}$	"	11	125

The relay 432 was therefore energized, closing by its right-hand armature a locking circuit for itself including the spring 455 top, and such relay will be maintained energ- 130

gized until the sequence switch leaves its ninth position. As the sequence switch 450 passes through its second position the closure and subsequent opening of the circuit of the power magnet of the 100's register over the spring 458 bottom will drive such register one additional position, that is in this case into its eighth position. Also as the sequence switch 450 passes through its 10 third position the translating relay 432 being locked up a circuit will be established over the spring 460 top, left-hand armature of such relay and spring 461 bottom, to drive the 100's register 429 from its eighth 15 into its ninth position.

On coming into its fourth position the sequence switch 600 being already in its third position, the fundamental circuit from the registering and controlling equipment is 20 closed to the group selector shown on Fig. 2. This circuit includes the line relay 242 of the group selector, and the selection controlling stepping relay 433 of said equipment, both of which relays will be energized. 25 This circuit also includes the springs 612, 473, 457 and 611 bottom. The energization of the relay 242 drives the sequence switch 600 into its fourth position over the spring 614, in which position the circuit for the tripping spindle power magnet 243 is closed and the tripping spindle starts in motion. In moving from position 3 to position 4, sequence switch 600 makes no changes in the fundamental circuit.

30 As the relay 433 was energized coincidentally with the energization of the line relay 242, it closed the circuit over the spring 458 top for the lower winding of the 100's register 429; the register, therefore, moved a half of a position, that is until the closure of the circuit through its upper winding and the positioning spring 471 thereof is closed. As the tripping spindle of the group selector began to move it intermittently closed a circuit to ground, such circuit being so connected to the fundamental circuit that when it is closed the relay 433 will be shunted and deenergized, though the line relay 242 is maintained energized. This deenergization 45 of the relay 433 will take place once for each movement of the tripping spindle one step or stage. Upon the deenergization of the relay 433 the 100's register again moves until it comes into its tenth position, from 50 which position it will be moved to a position intermediate between its tenth and eleventh positions, when the relay 433 is again energized as the tripping spindle comes into its set position to trip the first set of brushes of the group selector; in the continued motion 55 of the tripping spindle a second deenergization of the relay 433 takes place and the 100's register is moved into its eleventh position, to be moved again into a position intermediate between its eleventh and zero po-

sitions, when the shunt is again removed at the tripping spindle.

The next closure of the earth connection at the tripping spindle, and the consequent third deenergization of the relay 433 drives 70 the 100's register into its zero or normal position. In this position the spring 473 is open and consequently not only will the relay 433 remain deenergized when the connection to earth is broken at the tripping 75 spindle, but also the line relay 242 will be deenergized, both the fundamental circuit and the branch circuit to ground being now open. As soon as this occurs, the circuit for the tripping spindle power magnet 243 is 80 open at the front contact of the line relay 242, and the tripping spindle is brought to rest. Such tripping spindle, having moved three steps or stages, is now in position to release the third set of brushes on the brush 85 carriage of the group selector, as it will be recalled that a trunk line leading to the group of final selectors in which the desired line appears is to be found in the third bank or level of such group selector. 90

As the 100's register came into its zero or normal position, if the incoming sequence switch 400 is in its ninth position—that is, if tens and units registration is complete—a circuit will be closed including the springs 95 456, 472 and 410 to drive the outgoing sequence switch 450 into its sixth position, in which it is ready to control tens selection as soon as an idle trunk line to a proper final selector has been found and seized in 100 the group selector, as will be described. If the incoming sequence switch 400 is not as yet in its ninth position, the outgoing sequence switch 450 will remain in its fourth position, moving into its sixth position as 105 soon as the sequence switch 400 reaches its ninth position.

When the line relay 242 stopped the movement of the tripping spindle of the group selector, it also closed a circuit over its back 110 contact and the spring 602 top, back contact and armature of the relay 237, which is deenergized after the sequence switch 600 left its third position, and spring 607 bottom, to drive the sequence switch 600 into 115 its fifth position.

In the fifth position a circuit will be established for the group selector power magnet 244, including the spring 603 bottom, the back contact and armature of relay 237, 120 sequence switch spring 602 top and the back contact and armature of the line relay 242. The brush carriage of the group selector, therefore, will begin to move in its first movement, causing the proper set of 125 brushes to be released in the movement past the said tripping spindle and then causing such released brushes 245, 246 and 247 to make contact with the various sets of contacts in the selected level. So long as the 130

test brush 247 makes contact with the test terminals of trunk lines which are already engaged, insufficient potential will be found thereon to energize the relay 235 due to the fact that the low resistance winding of a relay corresponding to the relay 235 of some other group selector is already connected to the terminal multiplied to such test terminal. As soon, however, as the 10 brushes come in contact with a set of terminals individual to an idle trunk line, full potential will be found on the test terminal thereof, and a circuit will be established for the test relay 235 extending from battery at final selector over the spring 312 bottom, spring 314 top, the left winding of the relay 331, test conductor of the seized trunk line, test brush 247 of the group selector, right-hand high resistance winding of the test 20 relay 235, spring 605 top, power control test relay 237 and spring 606 top to ground. The test relay 235 will be energized, but the relay 237 will not be energized owing to the shunt therearound existing over the interrupter brush 244. The energization of the 25 relay 235 closes a low resistance circuit through its left-hand winding parallel to its right-hand winding, which so reduces the potential upon the test terminal of the trunk line that the test relay 235 of no other group selector, the brushes of which come in contact with the terminals of such line, will be energized. As soon as the brush carriage, which is continued in motion, properly centers the brushes upon the terminals of the seized line, the shunt circuit through the interrupter brush will be open and the relay 237 will be energized. The energization of this relay will open the circuit for the power 40 magnet 244 and close the circuit for the holding magnet 250 over the springs 608 top and 607 top, so that the brush carriage of the group selector will be properly and accurately stopped in the well-known manner. The energization of the relay 237 has also 45 closed a circuit for the sequence switch 600 to drive such sequence switch into its sixth position. In this position of the sequence switch 600 the fundamental circuit is connected through from the final selector to the registering and controlling equipment, and the closure of this circuit at this time depends upon whether the outgoing sequence switch 450 has reached its sixth position. When the sequence switch 450 was driven 55 out of its fourth position upon the completion of the hundreds selection controlling operation, it moved directly into its sixth position, but in passing through its fifth position the momentary closure of the spring 462 bottom has driven the tens register into its eleventh position in the now well-understood manner. When now the fundamental circuit is again closed in the sixth position 60 of the sequence switch 450, including the line relay 332 at the final selector, spring 308 top, brush 246 of the group selector, spring 617 bottom, spring 483 of the 10's register, spring 453 top, relay 433, spring 616 bottom, brush 245 of the group selector, 70 and spring 309 top to ground, the relays 332 and 433 are both energized. The energization of the relay 332 drives the sequence switch 300 into its second position by the closure of the circuit over the spring 303 top, in which position the circuit for the tripping spindle power magnet 333 is closed over the spring 302 bottom and the front contact of the relay 332. The tripping spindle will thereupon begin to move. The energization at this time of the relay 433 has closed a circuit over the spring 462 top to move the tens register one-half of a position from the position in which it was set as described. 80

It will be recalled that the 10's digit of the desired line is zero, and therefore such line is to be found in the first bank or level of the final selector. It will therefore be necessary that the selection controlling operation 90 of the final selector should be terminated when the tripping spindle has moved one step or stage and is in position to release the set of brushes corresponding to the first bank set or level of contacts. It will also be 95 recalled that the 10's register was set by the subscriber in its tenth position and subsequently moved to its eleventh position. When, therefore, the tripping spindle at the final selector moves its first step or stage, the 100 shunting of the relay 433 in the well-known manner drives the 10's register into its zero or normal position. This movement of the 10's register immediately opens the fundamental circuit at the spring 483 of such 105 register, so that when the shunt circuit through the tripping spindle is opened both the relay 433 and the relay 332 are deenergized. At the same time the closing of the spring 482 of the 10's register closed a circuit including the springs 411, 482 and 463 top to drive the outgoing sequence switch 450 into its eighth position ready to control 110 units selection, and the fundamental circuit which has been maintained open between the sixth and eighth positions of such sequence switch will there await its second closure at the final selector. Immediately upon the deenergization of the line relay 332 as just described the movement of the tripping 115 spindle is stopped, it being now in position to trip the first set of brushes on the brush carriage, and the sequence switch 300 is driven from its second position to come to rest in its fourth position. As the outgoing 120 sequence switch 450 of the registering and controlling equipment moved through its seventh position upon the termination of tens selection the momentary closure of the spring 454 moves the units register one addi- 125 130

tional position so that when the sequence switch stops in its eighth position and again closes the fundamental circuit the units register is in its fourth position. The closure at this time of the fundamental circuit again energizes the relays 332 and 433, but this time in the fourth position of the sequence switch 300 and the eighth position of the sequence switch 450. In the fourth position of the sequence switch 300 the energization of the relay 332 closes a circuit over the spring 306 top for the brush carriage power magnet of the final selector, and such brush carriage begins to move. In the initial movement of the brush carriage, the proper set of brushes (in this case the first set) is tripped as the carriage passes the tripping spindle. In the subsequent movement of the brush carriage the brushes 334, 335, 336 sweep over the sets of terminals individual to the lines multiplied to this bank or level of contacts. For each movement of such brushes to a set of terminals the interrupter device 337 closes a circuit to ground from the fundamental circuit over the springs 313 top and 315 in the well-known manner, such circuit to ground as is well understood shunting the relay 433 while maintaining the relay 332 energized.

Upon the energization of the relay 433 and its subsequent intermittent deenergization due to the shunting action of the contacts of the interrupter 337 at the final selector, the units register will be stepped in the well understood manner, one full position for each energization and subsequent deenergization of the relay 433. At the end of eight of such operations of the relay 433 the units register will again be in its normal position, the selected brushes of the final selector at this time being about to make contact with the eighth or No. 7 set of contacts of the bank or level to which they are individual. It will be recalled, however, that since the desired line is located in an odd hundred, the particular line desired is to be found in the second half of the final selector, and it is therefore necessary that the selecting operation should not terminate at this time. For this reason the fundamental circuit is not opened at this time at the spring 493 as would be otherwise the case, a shunt being maintained about such spring, such shunt including the spring 460 bottom, left-hand armature of the translating relay 432 and the spring 461 top. It will be recalled that the relay 432 was locked up when the sequence switch 450, in passing from its first to its second position, tested the condition of the 100's register 429, and on finding it in a position corresponding to an odd hundred, completed the circuit for the translating relay 432. The fundamental circuit not being open at this time, the brush carriage at the final selector will continue to

move until the units register 431 has made a complete revolution as a result of such movement. This means that the units register will take twelve additional steps. It will now be seen for what purpose the two additional notches in the interrupter plate of the final selector are provided, as hereinbefore described. To reach the contacts of the desired line after the units register has first reached its normal position would otherwise produce only ten deenergizations of the stepping relay 433, and consequently only ten steps by the units register.

Since it is necessary that the units register should come into its zero or normal position in order to cause the cessation of selection, it is necessary that two additional steps be provided for and, consequently two additional notches are cut in the interrupter plates of the final selector to produce such steps. Therefore, after the stepping relay 433 has been operated twelve additional times, and as the selected brushes of the final selector are coming into contact with the seventh set of terminals in the second half or range of the selected bank or level of the final selector, the units register will again be in its normal position.

As the units register passed its normal position without stopping, as above described, circuit was closed by the spring 492 over the spring 463 bottom to drive the sequence switch 450 out of its eighth and into its tenth position, this circuit being only maintained momentarily by the spring 492. The sequence switch stopped in its tenth position. When now the units register 431 comes a second time into its normal position the shunt around the spring 493 thereof being opened at the springs 460 bottom and 461 top, the fundamental circuit is immediately opened, producing the deenergization, in the manner well understood, of the relays 332 and 433 to terminate selection in the final selector. The units register 431 coming into its normal position again closes the spring 492, and the sequence switch 450 returns to its normal position, in which movement in passing through position 11 it closes a circuit at spring 455 bottom to return the sequence switch 400 to its normal position. It should be also noted that the sequence switch 450, on leaving its ninth position, opened the locking circuit of the translating relay 432. The desired line now having been selected, the services of the registering and controlling equipment are no longer required for this connection, and therefore as the sequence switch 400 left its ninth position the spring 406 opened the circuit for the relays 426 and 240, which circuit had been substituted for the one originally established over the spring 405 as the sequence switch 400 left its first position. The relays 426 and 240 are therefore deen-

ergized. The energization of the relay 426, and the restoration of the sequence switch 400 to normal will cause the registering and controlling equipment shown on Fig. 4 to 5 test idle and accessible to any connecting circuit taken for use which has access to it. At the same time that the relay 426 is deenergized the relay 240 was deenergized and by the retraction of its armature closed a circuit to drive the sequence switch 600 from its sixth into its seventh position. This is the through or talking position of this sequence switch. In this movement, however, the contact 611 top is closed and the sequence switch 200 is driven from its fourth into its fifth position. In these positions the sequence switches 600 and 200 await the further operations of the final selector apparatus shown on Fig. 3.

20 Upon the deenergization of the relay 332 at the completion of the units selecting operation, the sequence switch 300 is driven from its fourth position, and it will move to its sixth position. When the trunk line to 25 this final selector was first seized, it will be recalled that the seizing circuit included one of the windings of the relay 331 and the spring 314 top. This relay was therefore energized, and closed for itself a circuit to 30 take the place of the circuit through the spring 312 bottom, which is opened as the sequence switch 300 leaves its first position. As the sequence switch moves from its fourth to its fifth position, the spring 314 35 top is opened and 314 bottom is closed. The relay 331 is maintained energized, both of its windings now being included in the circuit and the battery is connected over the spring 314 bottom to the power control test relay 339. At the same time the spring 307 top is closed, connecting battery with a high resistance winding of the test relay 349. The fifth position of the sequence switch 300 is the testing position thereof. If in 40 this position full potential is found upon the test terminal 342 of the desired line, indicating that the line is idle, the test relay 349 will be energized over its right hand high resistance winding. If on the other 45 hand the normal potential upon such test terminal 342 is reduced by such line being busy, either as a calling line or a called line, as will occur in the well-known manner, the test relay 349 will not be energized. Assuming 50 first that the line is idle and that such relay is consequently energized; it closes over its armature a circuit, through its low resistance left-hand winding and the test relay 339, in parallel to its right-hand winding, which will so reduce the potential of the test terminal of such seized line that it will test busy in all other final 55 selectors in which it appears. Such circuit will also energize the relay 339 and when the sequence switch 300 comes into the sixth

position, it will find circuits closed, one over the spring 317 and the other over the spring 305 bottom, and the front contact of relay 339 and the back contact of relay 332, to move it into its tenth position, in which position, and also in the eleventh position a circuit will be found closed to move it into its twelfth position. The sixth position of this sequence switch is provided for hunting an idle line to a private branch exchange, in 70 case the particular line selected is found busy. The apparatus for performing this operation is not shown, however, and in order to drive the sequence switch through its sixth position, which is, as shown, an 75 idle position, whether the desired line is found idle or busy, the spring 317 is provided.

The twelfth position of the sequence switch 300 is the ringing position. In this 80 position ringing current is projected over the called line by the closure of the springs 310 bottom and 311 bottom.

As the sequence switch 300 passed through its eighth position, the trunk line leading to 85 its final selector was shortcircuited by the closure of the spring 309 bottom. This causes the momentary energization of the supervisory relay 248, which by the attraction of its armature drives the sequence 90 switch 200 into its eighth position. This would cause the subscriber to receive the busy tone by the closure of the springs 212 bottom and 213 top, except for the fact that almost immediately after as the sequence 95 switch 300 passes from its eleventh into its twelfth position, the spring 309 bottom is again closed energizing the relay 248 to drive the sequence switch 200 into its eleventh position. In this position of the 100 sequence switch 200, the springs 212 top and 213 bottom being closed, the subscriber receives the distinctive ringing tone, and will continue to receive such tone so long as the sequence switch 300 remains in its twelfth 105 position. So long as the called subscriber does not respond, insufficient current will pass over the ringing relay 343 to energize it. As soon, however, as the path for direct current is closed at the subscriber's substation, by the removal of his receiver from 110 its switchhook, the relay 343 will be energized and drive the sequence switch 300 into its thirteenth position. In this position the circuit is closed through from the battery 115 and repeating coil shown in Fig. 2 to the called subscriber's substation, and the relay 248 is therefore energized, driving the sequence switch 200 out of its eleventh and into its fourteenth position.

The sequence switch 100 being in its fifth position, the sequence switch 200 being in its fourteenth position, the sequence switch 600 being in its seventh position, and the sequence switch 300 being in its thirteenth po- 120 125 130

sition, the calling subscriber and the called subscriber are now connected, each subscriber being supplied with transmitter current from the battery shown in connection 5 with the repeating coil 239. Conversation may now take place.

The operation described is the normal operation in which an idle desired line is selected, seized and signaled, and the subscriber thereon responds. In such an operation it will be noted that the called supervisory relay 248 is three times energized, first to move the sequence switch 200 from its fifth position to its eighth position; next 10 to move such sequence switch from its eighth position to its eleventh position; and finally to move such sequence switch from its eleventh position into its fourteenth position. The importance of these three operations will later appear.

Disconnection and metering.—Disconnection in the system shown may take place under the control of either subscriber except that if either subscriber should be slow 15 in hanging up his receiver, or should neglect to hang up his receiver after the other subscriber has done so, the particular switch (first line finder in connection with the calling subscriber, and the final selector in connection with the called subscriber) will be maintained in an off-normal condition, in order that such subscriber may not seize and tie up a connecting circuit and registering and controlling equipment by his failure 20 to restore his receiver to its switchhook. However, the call having been successful, it is necessary that the metering operation should take place to charge a call to the calling subscriber, even in the case that both of 25 such subscribers restored their receivers to their hooks, or whether only one of such subscribers does so independent of whether such one subscriber is the calling subscriber or the called subscriber. If the calling subscriber should first restore the deenergization 30 of the calling supervisory relay 241 closes a circuit for the sequence switch 600 including the springs 252 and 209 bottom to drive such sequence switch from its seventh position into its eighteenth position. Similarly 35 the restoration of the called subscriber's receiver to its switchhook causes the deenergization of the called supervisory relay 248, which closes a circuit for the sequence switch 600 including the springs 203, 209 bottom, to move such sequence switch out of its seventh and into its eighteenth position. The restoration, therefore, by either of the parties of their receiver to its 40 switchhook causes such movement of the sequence switch 600. The movement of the sequence switch 600 out of its seventh position opens at the spring 610 the circuit of the relay 137 at the first line finder which 45 by the retraction of its armature closes a

circuit including the spring 105 bottom to move the sequence switch 100 out of its fifth position and into its ninth position. The movement of the sequence switch 600 into its eighth position closes a circuit including 50 the spring 609 bottom to drive the sequence switch 200 out of its fourteenth position and into its normal position. The sequence switches 600, 200 and 100 are therefore simultaneously moving, the sequence switch 600 having started from its seventh position, the sequence switch 100 having started from its fifth position, and the sequence switch 200 having started from its fourteenth position. Therefore as the sequence 55 switch 200 is passing through its fifteenth, sixteenth, and seventeenth positions, the sequence switch 100 during a part of this period, at least, will not as yet have reached its eighth position, and a circuit will therefore be established from the high potential battery 298 through spring 207 bottom, relay 135, spring 102 top, contact 131 individual to the calling line, and meter magnet 55 of the meter individual to such line. The 60 increased battery impressed upon the circuit including the meter magnet 55 and the cut-off relay 139 by the closure of the contact 137 bottom is sufficient to cause the energization of the meter magnet 55 thereby 65 causing the charging of a call against the calling subscriber. The remaining restoring operations of the system disclosed take 70 place in the usual manner.

On coming into its eighteenth position 75 the sequence switch 600 established the usual restoring circuit for the brush carriage of the group selector, and such brush carriage moves until the brush 244 of the interrupter comes in contact with the normal segment, at which time circuit is closed over the spring 618 to energize the relay 237 which stops the movement of the brush carriage in the usual manner and drives the sequence switch 600 into its normal position.

As the sequence switch 600 left its seventh position, it opened at the spring 610 top the circuit of the relay 137 at the first line finder. This relay thereupon, being deenergized, drives the sequence switch 100 from its fifth into its ninth position. In the eighth and ninth positions of this sequence switch a circuit for this relay is again established, provided the calling subscriber has not restored his receiver to its switch hook, which includes the spring 108 bottom, the spring 111, the substation circuit, and the spring 112 top. The sequence switch 100 will therefore stop in its ninth position and remain there until the subscriber opens the circuit to direct current at his substation by replacing his receiver upon its switchhook. As soon as this occurs, the relay 137 will again be deenergized and drive the sequence switch 100 back to its first or normal position.

tion. It will be observed that the cut-off relay 139 is controlled through the seventh position by a circuit including the spring 102 top, and in the eighth or ninth position by a circuit including the resistance 199 and the spring 110. This transfer of control is accomplished before the circuit of the cut-off relay 139 was opened at the spring 207.

As the sequence switch 600 left its seventh position, it opened at the springs 605 top and 606 top the circuit for the relay 331 at the final selector. This relay therefore immediately allowed its armatures to retract, its left-hand armature closing a circuit over the spring 308 bottom to energize the line relay 332. The energization of this relay drives the sequence switch 300 out of its thirteenth position into its sixteenth position. On coming into its sixteenth position, the circuit at the called subscriber's substation being already opened, the relay 332 is without current and therefore is de-energized, driving the sequence switch 300 into its eighteenth position. In this position of the sequence switch 300 the usual circuits are established to restore the switch carriage of the final selector to normal. When, however, the brush of the interrupter 337 comes in contact with the normal segment, circuit is again established to energize the relay 332 which, by the attraction of its armature, drives the sequence switch into its normal position. The entire apparatus is now in its normal position. It will be observed, however, that although the relay 331 at the final selector is deenergized immediately that the sequence switch 600 leaves its seventh position, it is not again energized by the closure of the spring 610 bottom, as such relay 331 controls through its right-hand armature the energizing current for itself in all positions, except position 1, of the sequence switch 300. However, in positions 8 to 17 a test guard is maintained on the terminal of the trunk line by the closure of the spring 610 bottom. At the final selector, however, when the sequence switch 300 comes into its fifteenth and sixteenth positions the called subscriber not as yet having restored his receiver to its switchhook, a circuit will be established for the relay 332, including the springs 308 top, 310 top, subscriber's line, 311 top and 309 top. Therefore, when the sequence switch 300 comes into its sixteenth position it will there stop and await the restoration of the called subscriber's receiver to its switchhook, which when it occurs, will open the circuit to the relay 332, allowing such relay to deenergize, to drive the sequence switch 300 out of its sixteenth position, after which the restoration of the final selector apparatus will take place as has been hereinbefore described.

65 *Attempted connection to a busy line.*—If

after the final selector switch has been moved to bring its brushes 334, 335, 336 into contact with the terminals of the desired line, and the sequence switch 300 is moving through its fifth and sixth positions, such line should be found busy, insufficient potential will exist upon the test terminal 342 to accomplish the energization of the relay 349, consequently, no energization of the relay 339 will take place and when the sequence switch 300 comes into its tenth position it will stop, and the restoration of the brush carriage of the selector will take place over a circuit including the armature and back contact of the relay 332, armature and back contact of the relay 339, and spring 306 bottom. It will be obvious, therefore, that as a result of the fact that the desired line is busy, but a single closure of the spring 309 has taken place, such closure being the one which takes place as the sequence switch 300 passes through its eighth position. This has resulted in but a single energization of the called supervisory relay 248, and the sequence switch 200 therefore stands in its eighth position, the busy tone being connected for a prolonged period across the connecting circuit by the closure of the springs 212 bottom and 213 top. The calling subscriber hearing the characteristic busy tone maintained on his line, will know that the line desired by him is busy, and initiates restoration by replacing his receiver upon its switchhook. It will be recalled that at this time the sequence switch 100 is in its fifth position, the sequence switch 200 is in its eighth position, and the sequence switch 600 is in its seventh position. The restoration of the calling subscriber's receiver to its switchhook causes the deenergization of the calling supervisory relay 241, which thereby completes a circuit including the spring 252 and the spring 209 top for the sequence switch 200. Almost immediately that the sequence switch 200 begins to move as a result of the closure of the circuit referred to, the spring 209 top is opened, and the spring 209 bottom is closed, so that a circuit caused by the deenergization of the calling supervisory relay 241 now exists for the sequence switch 600 which moves from its seventh position. Restoration now takes place in the first line finder and its associated parts, the second line finder connecting circuit, the group selector and its associated parts precisely as in the normal connection the sequence switches 100, 200, and 600 being simultaneously in motion, but it should be noted that these sequence switches have started from different relative positions from the positions in which they started in motion in a normal restoration—that is to say, while the sequence switch 100 has started as before from its fifth position and the sequence switch 100

600 has started as before from its seventh position, when such sequence switches started in motion the sequence switch 200 was moving through its eighth position instead 5 of from its fourteenth position as in restoration after a successful connection. It will be apparent, therefore, that before the sequence switch 200 can reach its fifteenth position in which the increased potential 10 battery 298 will be connected to the circuit of the cut-off relay of the calling line, in which circuit the meter of such line by the closure of the spring 207 bottom in the fifteenth, sixteenth and seventeenth positions 15 of the sequence switch 200, the sequence switch 100 will have passed into its eighth position, in which position the spring 102 top is opened, and it is therefore impossible for the increased battery to be impressed 20 upon the circuit of the cut-off relay and the meter, or for the metering operation to take place.

Called subscriber does not answer; no metering.—In case the desired line is idle, 25 the sequence switch 300 at the final selector moves directly into its twelfth position as has been before described. During such movement of the sequence switch 300, the sequence switch 600 is in its seventh position, 30 and the spring 309 of the sequence switch 300 having been closed twice during the motion of such sequence switch into its twelfth position, that is first in its eighth position and second between its eleventh and its 35 twelfth positions, the called supervisory relay 248 has been twice energized, and as a result the sequence switch 200 has first been moved from its fifth into its eighth position, and then moved from its eighth position into 40 its eleventh position in which position it now stands. At this time the calling subscriber hears the ringing tone, and knows that the called subscriber is being signaled. If the called subscriber does not respond before the 45 calling subscriber restores his receiver to its switchhook, the connection will be severed. The deenergization of the calling supervisory relay 241 closes the circuit including the springs 252 and 209 bottom, to drive the 50 sequence switch 600 out of its seventh position and into its eighteenth position. This movement of such sequence switch initiates the movement of the sequence switches 100 and 200 precisely as in disconnection after a 55 successful call, except that whereas the sequence switch 100 starts in motion from its fifth position as in restoration after a successful call, the sequence switch 200 starts in motion from its eleventh position instead of 60 from its fourteenth position. Therefore before the sequence switch 200 can come into its fifteenth position in which the spring 207 bottom will be closed to apply increased battery potential to the circuit of the cut-off 65 relay and meter of the calling line to pro-

duce the metering operation, the sequence switch 100 will have reached its eighth position in which the spring 102 top being opened the metering operation is prevented. In all other respects restoration as a result 70 of the abandonment of a call by the calling subscriber when the called subscriber is being signaled but has not responded, takes place as has been described in connection with the restoration after a successful call. 75

Premature disconnection.—If at any time after the calling line has been extended to the connecting circuit as shown in Fig. 2, and before the called line has been tested, the calling subscriber should abandon the 80 call, no metering operation will take place. If the calling subscriber restores his receiver to its switchhook in the third position of the sequence switch 200, relay 241 becomes deenergized and a circuit is closed from ground 85 through sequence switch spring 252 top, back contact and armature of relay 241 and sequence switch spring 209 bottom to drive sequence switch 600 out of its third position and into its fourth position. The stepping 90 relay also becomes deenergized and upon the restoration of the receiver, causes the energization of the change-over relay 428, and the relay 427 remaining deenergized and the relay 428 energized, the incoming sequence 95 switch 400 will be driven directly into its ninth position from whatever position it may be at the time. When sequence switch 400 reaches its ninth position, the sequence switch 200 is driven from its third into its 100 fourth position as has been hereinbefore described. When sequence switch 600 is driven out of its third position, relay 240 becomes deenergized and closes a circuit from ground through its armature and back contact and sequence switch spring 613 top for sequence switch 600 and sequence switch 600 is driven 105 out of its fourth position into its seventh position. The sequence switch 200 will then be further driven into its eleventh position 110 by the closure of a circuit over the back contact of supervisory relay 241, and from such position the group selector apparatus, the sequence switch 600, the sequence switch 200, and first line finder apparatus and the 115 final selector apparatus, if it has been seized and moved from normal, will be restored to normal condition, as has been hereinbefore described. As sequence switch 200 comes into its ninth position, a circuit is again 120 closed over the spring 209 and the back contact of the relay 241, and the sequence switch 600 which moves out of its seventh position, and will continue in motion until it reaches its eighteenth position. From this point it will be obvious that the restoring operations would be the same as those which took place in connection with an attempted call to a busy line, and as in such case no metering 125 operation will take place due to the fact that 130

the sequence switch 100, starting from its fifth position in response to the opening of the spring 610 as the sequence switch 600 reaches its seventh position, will have passed 5 into its eighth position in which metering is impossible, before the sequence switch 200 reaches its fifteenth position in which the metering circuit would otherwise be closed by the closure of the spring 207 bottom.

10 Obviously the same operation will take place as just described if the calling subscriber abandons the call in position 3 of the sequence switch 200.

If the calling subscriber abandons the call 15 in either position 4 or 5 of the sequence switch 200, such sequence switch would be moved into its eleventh position by the circuit including the back contact of the relay 241 and the spring 209 top. In this position

20 it would await the movement of the sequence switch 600 into its eighth position, as the result of the normal operation of such sequence switch or the closure of the circuit including the spring 209 bottom. However,

25 as the sequence switch 600 reached its seventh position, and before it came into its eighth position to start the sequence switch 200 in motion from its eleventh position, it initiated, by the opening of the spring 610, the movement of the sequence switch 100 from its fifth position, and the sequence switches 100, 200 and 600 would therefore simultaneously move, producing the restoration of the circuits and apparatus shown precisely as in

30 the case of the abandonment of the call by the calling subscriber while the called subscriber was being signaled, but before he had responded. No metering operation will therefore take place in the case assumed of 35 the abandonment of the call in the fourth or fifth positions of the sequence switch 200.

It will be obvious from the description given that the metering operation is controlled by the sequence switches 100, 200 and 45 600, the sequence switches 100 and 200 entering directly into such control and the sequence switch 600 controlling, in part at least, the other sequence switches. It will be obvious that metering will take place inevitably in case of a successful call. No metering is possible in case either of an unsuccessful or an abandoned call.

50 *Register controller mechanism supervisory signals.*—Associated with the registering controlling mechanism are the signals 497, 498, 499. The spring 464 being closed in the fourth position of the sequence switch 450 causes the lamp 497 to light, indicating that the hundreds selecting controlling operation is taking place. Correspondingly the closure of the spring 465 in the sixth position lights the lamp 498 to show that the tens selection controlling operation is taking place, and also correspondingly its closure at its bottom contact in the eighth and tenth positions and

the consequent lighting of the lamp 499 indicates that the units selection controlling operation is taking place. These lamps serve to indicate to an attendant at what stage of its operation the registering controlling mechanism may be, and the prolonged lighting of one of these lamps will indicate some trouble which has held up the connection in the particular stage indicated by the lamp.

Establishing untranslated connection.—In 75 the establishment of the connection hereinbefore described, it has been assumed that the number of the desired line was 307, in which case it was necessary that the desired line be selected in the second half or range of the final selector, and further that it was necessary that a second additional movement of the 100's register 429 be produced by the closure of the spring 460 top.

To illustrate how a call will be selected in 80 the first half or range of the final selector it will be assumed that the desired line is designated 207. In this case obviously the tens register 430 and the units register 431 are set as hereinbefore described, in their tenth and third positions respectively and by the subsequent steps produced by the springs 462 bottom and 454 bottom, control the selection controlling operations from the eleventh and fourth positions respectively as hereinbefore described. The 100's register, however, will be set by the subscriber's sender in its eighth position, eight impulses having been received from the substation sender to indicate the 95 100's digit 2.

When the sequence switch 450 moved from 100 its first to its fourth position, preparatory to the initiation of the 100's selection controlling operation as it passed between its first and second position, the spring 459 was closed, but as the 100's register 429 was in an even position—in this case its eighth position—no circuit was established for the translating relay 432 at spring 474, and such relay is therefore not energized, and cannot 110 be energized subsequently in the establishment of the desired connection. As the sequence switch 450 passed through its second position, the additional movement of the 100's register 429 one step or position is produced by the closure and subsequent opening of the spring 458 bottom. In passing through its third position no second movement of the 100's register 429 takes place, even though the spring 460 top is closed, 115 for the reason that the translating relay 432 is not energized, and the circuit including the spring 460 top and the 100's register is therefore not closed. The 100's selection therefore will be controlled by the 100's register 429 from its ninth position and the group selector will be operated to select an idle trunk to a final selector in its third row of contacts as hereinbefore described, it

120 125 being recalled that the trunk lines leading 130

to the panel selectors having access to lines whose 100's digit is 2 and also whose 100's digit is 3 are in the third row of contacts of the group selector. Tens selection will 5 take place in the present instance precisely as has been hereinbefore described. Units selection, however, will be terminated in the present instance when the units register 431 first returns to its normal position—that is 10 after such units register has been moved eight steps to control the selection of the eighth or No. 7 set of terminals in the first range of contacts in the selected level of the final selector. This result is produced 15 by reason of the fact that no circuit to maintain the fundamental circuit closed exists in the eighth and ninth position of the sequence switch 450 as hereinbefore described through the spring 460 bottom, left armature of the 20 translating relay 432 and spring 461 top. The fundamental circuit will therefore be opened at this time, causing the cessation of selection at the final selector and the sequence switch 450 will be driven continuously 25 through its ninth and tenth positions by the closure of the spring 463 bottom, coming to rest only when it reaches its normal position. It will therefore be seen that the translating relay 432, which tests the condition 30 of the 100's register 429 as set by the subscriber, determines whether it is necessary that the 100's register be given the additional movement of one position, and also determines whether the desired line is to be found in the first half or second half of the 35 selected level in the final selector.

It will be obvious from this description that for any number desired by the calling subscriber, the impulses received from the 40 substation when the substation sender is operated in accordance with the designation of the desired line will so set the registers at the central office that connection with the desired line will be accurately and 45 positively accomplished.

I claim:—

1. In a telephone exchange system, automatically operating switches over which a connection is extended from a calling line 50 to a called line, a sequence switch having a plurality of contacts for controlling one of said automatically operating switches, said sequence switch being movable in one direction only, means responsive to the initiation 55 of severing of said connections for restoring said sequence switch, a meter associated with the calling line, and a meter operating circuit closed only under the control of contacts of said sequence switch if 60 the initiation of restoration of said sequence switch takes place when the sequence switch is in a given position.

2. Telephone exchange system comprising automatically operating switches over which 65 a call may be extended from a calling to a

called line, two sequence switches associated with the circuit as extended, a plurality of contacts for said sequence switches, means for starting said sequence switches in motion upon the initiation of restoration, a 70 meter associated with the calling line, an operating circuit for said meter controlled by the contacts of said sequence switches one of such sequence switches being adapted to close at one of its contacts such meter operating circuit when moved upon the initiation of restoration, and the other of such sequence switches being adapted to open at one of its contacts the meter operating circuit when moved upon the initiation of restoration. 75

3. In a telephone exchange system, automatically operating switches over which a connection is extended from a calling line to a called line, two sequence switches movable only in one direction for controlling 80 said automatically operating switches, means controlled by the called line for moving one of said switches into a definite position, a meter associated with the calling line, a meter operating circuit controlled only by 85 contacts of said sequence switches, means for restoring said sequence switches upon the severing of said connection, and means for closing said circuit only if one of said sequence switches is restored from a definite 90 position. 95

4. Telephone exchange system comprising automatically operating switches whereby the circuit of a calling line may be extended to a called line, a meter associated with the calling line, a sequence switch by which the circuit of said meter is extended to a second sequence switch associated with the circuit of the calling line as extended, means for moving said second sequence switch to a 100 position more or less advanced responsive to the condition of the called line, a relay for initiating disconnection starting both of said sequence switches in motion in such disconnecting operation, such first sequence switch 105 in such movement opening such meter operating circuit, said second sequence switch in such motion closing such meter operating circuit before the opening of said circuit by said first sequence switch only if such second sequence switch is in an advanced position 110 initiating disconnection. 115

5. In a telephone exchange system, a plurality of lines, automatically operating switches for establishing a connection between a calling and a called line, a sequence switch associated with each of said switches, said sequence switches being movable in one direction only, means controlled by the 120 called line for moving one of said sequence switches to a definite position, and means for closing said operating circuit only under the control of contacts of said sequence switches if one of said sequence switches has 125 been moved to said definite position. 130

6. In a telephone exchange system, automatically operating switches for establishing a connecting circuit between a calling and a called line, a sequence switch associated with said connecting circuit, said sequence switch being movable in one direction only, means controlled by the called line for moving said sequence switch to a definite position, and means for moving the sequence switch to another position if the called line is busy, a meter associated with the calling line, a second sequence switch for extending a circuit of said meter to a contact of said first mentioned sequence switch, and means operative only if said first mentioned sequence switch has been moved to said definite position for closing the circuit of said meter only under the control of contacts of said sequence switches.
7. In a telephone exchange system, means for establishing a connecting circuit between a calling and a called line, two sequence switches associated with said connecting circuit and movable in one direction only, a meter associated with the calling line, contacts for said sequence switches, a meter operating circuit, the closed or open condition of which is controlled only by said contacts after the establishment of said connecting circuit, and means for closing said meter operating circuit only when in the restoring movement of such sequence switches one of them is advanced to a position to close such metering circuit before the other of said sequence switches reaches a definite position.
8. Machine switching telephone system comprising a connecting circuit to which a calling line may be extended, a selector switch associated with said connecting circuit for further extending the circuit of the calling line, a final selector switch by which the circuit of the calling line may be still further extended, a sequence switch associated with said final selector switch adapted to move into a definite position if the called line is busy into another position to signal such line if idle, and into another position upon the response of the subscriber on such line, a busy tone circuit associated with said connecting circuit, a ringing tone circuit associated with said connecting circuit, a sequence switch associated with said connecting circuit, such sequence switch being responsive to the operation of the sequence switch associated with the final selector to move into one position to connect the busy tone circuit to the connecting circuit, to move into another position to connect the ringing tone circuit to the connecting circuit, and to move into still another position if the subscriber on the desired line responds, a meter associated with the calling line, means forming a part of said connecting circuit sequence switch for closing an operating circuit for said meter in its restoring movement, and a third sequence switch for preventing the closure of such meter operating circuit except when said connecting circuit sequence switch starts in its restoring movement from the position to which it would be moved if the desired line is found idle and the subscriber thereon responds.
9. Telephone exchange system comprising automatically operating switches for extending a calling line, two sequence switches associated with said line as extended, contact for said sequence switches, a meter associated with said calling line, an operating circuit for said meter completed by contacts of said sequence switches in the restoring operations if the restoring movement of such sequence switches bear a definite relation to one another and maintained open by contacts of said sequence switches if the restoring movements of said sequence switches bear any other relation to each other.
10. In a metering system for telephone exchanges, an electromagnetic metering device, an operating circuit therefor, a plurality of sequence switches, contacts for said sequence switches, means for maintaining said operating circuit normally open at a plurality of contacts of said sequence switches, means for simultaneously closing said contacts if an initiated call has been successful, and for preventing the simultaneous closing of such contacts if the call has been unsuccessful, said operating circuit being controlled only by the contacts of said sequence switches.

In witness whereof, I hereunto subscribe my name this 17th day of February A. D. 1914.

LIPA POLINKOWSKY.
